UNITED STATES PATENT OFFICE

2,509,640

MACHINE GUNLOCK

Percy Reuben Higson, Westminster, London, England, assignor to Vickers-Armstrongs Limited, London, England, a company of Great Britain

Application November 2, 1946, Serial No. 707,394
In Great Britain October 29, 1945

Section 1, Public Law 690, August 8, 1946
Patent expires October 29, 1965

2 Claims. (Cl. 89—151)

1

This invention relates to machine guns of the barrel recoiling type, and generally known as the "Vickers" type in which, as shown in United States Patent No. 2,013,312, the firing pin is operated during the locking action of a side lever to which is connected the recoil of the spring, this side lever actuating a reciprocating breech block with which is associated a firing pin operated during the locking action of the side lever, this side lever, in effect acting as a connecting rod across the reciprocating breech block and a crank having an axis of oscillation substantially intersecting an axis containing the aforesaid side lever and breech block when in the firing position, so that when in the firing position the side lever and crank occupy substantially a dead-centre relationship but move to angular relationship when the breech block is withdrawn. The object of the invention is to simplify considerably the locking and firing mechanism so as to dispense with the cocking of the firing pin.

According to the present invention a machine gun of the "Vickers" type in which the firing pin is operated during the locking action of a side lever actuating a reciprocating breech block, is characterised in that the firing pin is displaceable to the firing position in and relatively to the breech block, and the side lever drives the firing pin forwardly relatively to the breech block to fire the gun upon closing the breech.

In carrying one form of the invention into practice there is combined with means for translating the cartridges successively from the feed box to the barrel, a side lever pivoted to the breech block accommodating the firing pin and extractor, the firing pin and the said lever having co-operating opposed parts adapted to be abutted together when the lever is moved into the locked position, the arrangement being that the forward movement and the firing of the cartridges is controlled by the contact between the side lever and the firing pin when bringing the firing mechanism to the locked position.

In order that the invention may be clearly understood and readily carried into effect, drawings are appended hereto illustrating an embodiment thereof, and wherein,

Figure 1 is a broken sectional side elevation of a Vickers machine gun breech mechanism in the firing position and embodying the present invention,

Figure 2 is a sectional side elevation showing the breech mechanism with the breech block

2

a full recoil and with a round positioned ready for ramming into the breech,

Figure 3 is a sectional elevation of the breech in the firing position and firing the last round, and

Figure 4 is a sectional elevation showing the cartridge case of the last round being ejected.

Referring to the drawings, the breech block is in the form of a housing 1 for the firing pin 5 and is formed at its rear end with a pendant abutment 2 adapted to trip over a spring loaded sear 3 which normally prevents forward translative movement of the housing 1 and the cartridge C² which is held by its rim in known manner between the flanges 17a of a guide 17 upstanding from the front end of the housing 1, the round being held in alignment with the barrel B when the housing is held back by the sear 3 (as shown in Figure 2) by the downward pressure of the lower front corner part 15a of a carrier 15 reciprocating in the guide 17, the cartridge being abutted against a stop in the form of a spring loaded detent 4 accommodated in the front end of the housing immediately subjacent the tapered bore 5a receiving the operative end of the firing pin 5, the firing pin body reciprocating in the cylindrical bore 6 of the housing. In this connection the firing pin has only a very small displacement relatively to the housing e. g. not more than one eighth of an inch, the forward movement of the firing pin relatively to the housing being against the influence of a coiled compression spring 7 interposed between a step 9 protruding inwardly at the front end of the bore of the housing and a step 8 formed in the front end of the body part of the firing pin. The reason for this very small relative displacement of the firing pin and the housing is because, that by means of the present invention, the customary cocking of the firing pin is dispensed with, the forward movement and the firing of the cartridge being controlled by the contact between a side lever 10 and the firing pin at the time the mechanism closes to the locked position. That is to say the round is fired by actual positive displacement of the firing pin forwardly against the influence of the spring 7 as the lever 10 completes its forward or loading action. This positive displacement, or forward pushing of the firing pin relatively to the housing 1 is obtained by the provision on the rear part of the firing pin of an abutment surface 11 located at a suitable angle, e. g. 45° to the axis of the firing pin, and a corresponding surface 12 formed on the side lever approximately midway between its ends,

the front end of the side lever being part of a known toggle action device and being pivoted to a pin 13 passed transversely through the front part of the housing 1, the firing pin being slotted longitudinally as at 14 to accommodate such transverse pin and to afford the requisite clearance for the reciprocation of the firing pin within the housing. The firing pin is forced forwardly to fire the cartridge by a face 12 on the side lever striking the face 11 on the firing pin at the instant the toggle action on the side lever closes and the mechanism is locked.

To fire, the sear is depressed, and until it is released, the housing 1 carrying the cartridge C¹ with it moves forward until the cartridge case is fully home in the breech and the firing pin makes effective driving contact with the base of the cartridge contemporaneously with the movement of the side lever 10 into axial or parallel alignment with the barrel B as shown in Figure 1. By this means cocking mechanism for the firing pin is obviated.

The cartridges are transported from the feed box 18, which is disposed immediately above the breech, to the barrel by the guide 17 which receives the rim of the appropriate round as aforesaid, and the round is urged along the flanges 17a simultaneously by the downward movement of the carrier 15 in channels 16 in the guide 17, thus ultimately bringing the appropriate cartridge into engagement with the aforesaid spring loaded detent 3 (see Figure 2) in order that the cartridge may be located correctly at the front end of the housing and supported in co-axial alignment with the barrel. The reciprocating movement of the carrier vertically relatively to the axis of travel of the housing is controlled by an island type cam, i. e. spaced and opposed inclined cam surfaces 19 19', 20 and 20' on a side plate 21 and top cover 22 respectively. That is to say the downward movement of the carrier 15 is effected during the rearward travel of the horns 15' along the rear or descending part 19' of the upper cam surface, and also during the forward movement of the horns 15' along the forwardly descending part 20' of the lower cam surface, the return or upward movement being derived from the cam or ramp surfaces 20.

When a round has been fired its case is withdrawn as the breech block is retracted, by reason of the interengagement of the cartridge case rim and the flanges 17a and in due course is ejected by the succeeding round forcing the empty cartridge case downwards over the detent 4.

Assembled to the said carrier 15 is a spring loaded ejector 23 pivoted on a pin 24 to a slide 25 slidably supported by the carrier for slight vertical reciprocation relatively to the carrier 15, this ejector operating to eject the case of the last cartridge from the lower end of the flanges 17a, the flanges in effect forming a T-section slot in the guide 17 to receive the cartridge case rims. This ejector is deflected as shown in Figure 1 by the cartridge C¹ in the feed box, and is thereby caused to be inoperative until there is no cartridge in the belt, when as shown in Figure 3, the ejector is urged slightly forward by its spring 26 and with the slide 25 is carried down with the carrier to its lowermost position as shown in Figure 4 to eject the cartridge case C².

of the last fired cartridge over and beyond the aforesaid spring loaded detent 3. For this latter operation the front edge of the slide is formed with a recess 27 dimensioned to receive readily the ejector 23, the ejector comprising a finger pivoted to the slide and spring loaded forwardly as aforesaid by the coiled compression spring 26, the arrangement being such that the lower part of this ejector is prevented from moving forwardly under the influence of such spring by reason of its engagement with the base of the appropriate cartridge C¹ in the feed box, but following the removal of the last round in the feed box the ejector 23 is free to move forwardly on its pivot so that its lower end bears against the uppermost point of the base of the cartridge case and pushes such case downwardly beyond the spring loaded detent. Excepting when the last cartridge case is to be ejected the ejector 23 is prevented from being pressed forwardly by its spring 26 when the cartridge C is positioned (as in Figure 2) in the loading position, by the lower edge of this ejector abutting against a step 28 on the front end of the breech block, thus causing the extractor to be pushed upwards relatively to the carrier so that the lower part of the extractor lies behind the corner piece 15a of the carrier. The extractor is formed with a recess or step 23a adapted to slip over the corner piece 15a when the extractor comes opposite the empty feed box 18 (see Figure 3) so that it cannot now be moved upwardly relatively to the slide 25 and forms a positive abutment to engage and eject the last cartridge case as in Figure 4.

35 I claim:

1. In a machine gun of the "Vickers" type a side lever, a reciprocating breech block actuated by said side lever, a firing pin displaceable in and relatively to the breech block, and co-operating opposed abutment surfaces on the side lever and firing pin which abut together when the side lever is moved into a position to lock the breech, said firing pin being urged forwardly by reason of said engagement of the abutting surfaces at the completion of the locking movement of the side lever to fire the gun.

2. In a machine gun of the "Vickers" type in which the firing pin is operated during the locking action of a side lever actuating a reciprocating block, a body slidable within the breech block and carrying the firing pin, a trailing cam surface on said body, a co-operating abutment surface on the side lever to engage the said cam surface when the lever is in the breech-closed position, and spring means yieldingly opposing forward displacement of the firing pin to the firing position and operating to present the cam surface of the said body for engagement by the said abutment surface of the side lever.
